CLAIM

We claim the ornamental design for a combined television and base, as shown and described.

DESCRIPTION

FIG. 1 is a top perspective view of a combined television and base of the present invention;

FIG. 2 is a front view thereof;

FIG. 3 is a first side view thereof, wherein the second side view is a mirror image thereof;

FIG. 4 is a rear view thereof;

FIG. 5 is a top view thereof;

FIG. 6 is a bottom view thereof;

FIG. 7 is a top view thereof, wherein the television is in a first alternative position;

FIG. 8 is a top view thereof, wherein the television is in a second alternative position; and,

FIG. 9 is a top view thereof, wherein the television is in a third alternative position.
